UNITED STATES PATENT OFFICE.

LEVI W. NACE AND EDGAR J. FINK, OF HANOVER, PENNSYLVANIA.

MITER-BOX.

1,257,099.

Specification of Letters Patent. Patented Feb. 19, 1918.

Application filed September 12, 1917. Serial No. 191,001.

To all whom it may concern:

Be it known that we, LEVI W. NACE and EDGAR J. FINK, citizens of the United States, residing at Hanover, in the county 5 of York and State of Pennsylvania, have invented new and useful Improvements in Miter-Boxes, of which the following is a specification.

This invention relates to improvements in 10 miter boxes, the object of the invention being to provide an improved miter box having an adjustable saw guide which may be readily arranged and secured at any desired angle, to enable any desired saw cut to be 15 made; another object of the invention being to provide an improved miter box which embodies means for clamping the work and holding the same securely while being sawed; a further object being to provide 20 an improved miter box of this character, which is cheap and simple in construction, is strong and durable, which is very compact and which can be readily arranged for use on a work bench or other like support.

25 The invention consists in the construction, combination and arrangement of devices hereinafter described and claimed.

In the accompanying drawings:

Figure 1 is a plan of a miter box constructed and arranged in accordance with 30 my invention.

Fig. 2 is a side elevation of the same.

Fig. 3 is a vertical longitudinal sectional view of the same on the plane indicated by 35 the line 3—3 of Fig. 1.

Fig. 4 is a vertical transverse sectional view on the plane indicated by the line 4—4 of Fig. 1.

Fig. 5 is a detailed elevation of the saw 40 guide and its segment base.

Fig. 6 is a detailed sectional view on the plane indicated by the line 5—5 of Fig. 1.

Fig. 7 is a perspective view of our improved miter box.

45 In the embodiment of our invention we provide a base box 1 which is open on the under side and comprises a top 2 and vertical side walls 3. The base box is adapted to be secured on a work bench or the like and to be arranged over the work, being indicated at a. The base box is open at the ends so that the work can be arranged therein and moved longitudinally.

50 To enable the base box to be secured on the bench the same is provided with points

4 which are pivotally secured on the outer sides of the walls 3 by means of screws 5 and which can be arranged in vertical position, to extend below the walls and in the 60 bench or can be turned upwardly against the wall out of the way. When the points are in bench engaging position they are secured to the walls by screws 6 in addition to the pivot screws 5. The walls of the base 65 box are also provided with eyes 7 which project outwardly therefrom and through which nails or the like, as at 8, may be driven into the bench.

One end of the top of the base box projects longitudinally beyond the side walls as at 10 and is mitered on opposite sides as at 11. A saw guide 12 is provided on one side with a semi-circular or segment base portion 13 which bears on the extension 10 and is 70 pivoted as at 14, the pivot 14 being here shown as a bolt which also secures the outer end of an arm 15. The said arm bears on the segmental base of the saw guide and the inner end of the said arm bears directly on 80 the top of the base box as at 16 and is secured thereto as by means of screws 17. The segmental base of the saw guide is provided with a scale 18 indicating degrees and is also provided at suitable points with 85 spaced openings 19. A clamping screw 20 extends through the arm 15 and may be caused to bear against the segmental base of the saw guide to secure the saw guide in adjusted position. A dog 21 is pivotally 90 connected to the inner end of the arm 15 as at 22 and is provided at its outer end with a point 23 which operates in an opening 24 in the arm and may be engaged in any one of the openings 19 of the saw guide to secure 95 the latter at any desired adjusted position. A spring 25 is arranged on the pivot 22 and with its arms or ends respectively engaging the dog and the top of the base box, the said spring exerting its tension to normally hold the dog in engaged position.

The saw guide with its segmental base is made of a single piece of sheet or plate metal and comprises an inverted U-shaped portion 26 the arms 27, 28 of which are 105 united at their upper ends by diametrically enlarged eyes 29 as shown. The eyes constitute springs which tend to move the arms 27, 28 toward each other to cause the arms to bear snugly against opposite sides of the 110 saw and to hold the latter straight while being used to make it cut. The arms of the

saw guide are also provided at one side with spring fingers 30 to frictionally engage the saw.

- The top of the base box has an opening 31 of suitable shape and dimensions, to expose the work and at opposite sides of the base box and near one end of said opening are upwardly extending lugs 32 in which a screw 33 is mounted and has its bearings. 5
- 10 The screw is provided at one end with a hand wheel 34 and has a stop collar 35 at the opposite end. A clamping arm 36 for engaging one side of the work is provided with a head 37 which has a threaded 15 opening through which the screw extends. Hence the said clamping arm may be adjusted by turning the screw to cause the work to be firmly clamped between said arm and one side of the base box as shown in 20 detail in Fig. 4.

Copies of this patent may be obtained for five cents each, by addressing the "Commissioner of Patents, Washington, D. C."

While we have herein shown and described a preferred form of our invention, we would have it understood that changes may be made in the form, proportion and construction of the several parts, without departing from the spirit of our invention and within the scope of the appended claim. 25

Having thus described our invention, we claim:

A miter box having a hollow base arranged to receive the work therein and also provided with an opening, a clamping screw mounted on the base and a clamping arm extending through said opening and into the hollow base to engage the work, said clamping arm having a head engaged by the screw. 30

35 In testimony whereof we affix our signatures.

LEVI W. NACE.
EDGAR J. FINK.
